(57) **CLAIM**

The ornamental design for a cap for quick connectors, as shown and described.

DESCRIPTION

FIG. 1 is a perspective view of cap for quick connectors showing my new design;

FIG. 2 is a front elevational view thereof; with the top and the bottom being identical to that shown;

FIG. 3 is a rear elevational view thereof;

FIG. 4 is a left side elevational view thereof;

FIG. 5 is a right side elevational view thereof; and,

FIG. 6 is a perspective view thereof, wherein the broken line structure is for illustrative purposes only and forms no part of the claimed design.
